UNITED STATES PATENT OFFICE.

THOMAS J. WHITNEY AND IGNATIUS HAAZ, OF PHILADELPHIA,
PENNSYLVANIA.

DESIGN FOR A FLAGSTAFF.

SPECIFICATION forming part of Design No. 29,194, dated August 9, 1898.

Application filed June 28, 1898. Serial No. 684,693. Term of patent 7 years.

To all whom it may concern:

Be it known that we, THOMAS J. WHITNEY, a citizen of the United States, and IGNATIUS HAAZ, a subject of the Emperor of Austria-Hungary, residing in the city and county of Philadelphia, State of Pennsylvania, have invented and produced a new and original Design for a Flagstaff, of which the following is a specification, reference being had to the accompanying drawings, forming part thereof.

The leading feature of our design for a flagstaff is a staff having the flag-attaching section widened or flaring at its lower portion, from which point it continues in the form of a cylinder of substantially uniform diameter to a point near its outer extremity, at which point said section is narrowed or tapered, while the grip or handle section extends downwardly from said flag-attaching section and is of greater diameter than the latter.

Figure 1 represents a side elevation of a flagstaff embodying our design. Fig. 2 represents a longitudinal section of Fig. 1.

In the drawings, A designates a flagstaff,

the same consisting of the sections A' B, the section A', constituting the flag-attaching section, being flaring or widened at its lower portion C, thence continuing in the form of a cylinder D of substantially uniform diameter to the point E, at which point it is tapered or of conical shape, the outer extremity of said flag-attaching section being of less diameter than any other portion. The section B constitutes the grip portion of the staff and extends downwardly from the section A' and is of greater diameter than the latter. At the place of junction of the two sections is the shoulder F.

Having thus described our invention, what we claim as new, and desire to secure by Letters Patent, is—

The design for a flagstaff, substantially as described and shown.

THOMAS J. WHITNEY.
IGNATIUS HAAZ.
